UNITED STATES PATENT OFFICE.

FREDERICK SCHRAY, OF BUCHANAN, MICHIGAN, ASSIGNOR TO THE BUCHANAN MANUFACTURING COMPANY, OF SAME PLACE.

FOLDING BED.

SPECIFICATION forming part of Letters Patent No. 320,298, dated June 16, 1885.

Application filed September 24, 1884. (No model.)

To all whom it may concern:

Be it known that I, FREDERICK SCHRAY, of Buchanan, in the county of Berrien and State of Michigan, have invented new and useful 5 Improvements in Folding Beds; and I do hereby declare that the following is a full, clear, and exact description thereof, reference being had to the accompanying drawings, which form a part of this specification.

10 The nature of this invention relates to certain new and useful improvements in folding beds; and the invention consists in the peculiar construction of the joint in the side rails, and in the peculiar construction, arrangement, 15 and various combinations of the parts, all as more fully hereinafter set forth.

Figure 1 is an end elevation with the bed closed, showing the position of parts in dotted outline. Fig. 2 is a perspective of the side 20 rails opened out and their various attachments. Fig. 3 is a vertical longitudinal sectional elevation of one of the joints of the side rail open. Fig. 4 is a similar view closed. Fig. 5 is a sectional elevation of one of the saddles, and Fig. 25 6 is a vertical section of the same.

In the accompanying drawings, which form a part of this specification, A represents a suitable case divided into two parts, forming the head-section *a* and foot-section *b*. This 30 case may be made in any desired form—for instance, such as representing a cabinet, as shown.

B represents the side rails, the outer ends of which are connected together by the transverse rails C, to which may be secured a woven-wire mattress, D', and which latter may be provided with any of the known mechanical devices for stretching and tightening the same. The inner ends of these side rails, B B, are 40 provided with intermeshing cogs, the two upper cogs in each pair of the side rails serving as a lock when the bed is extended, so as to limit the downward radial movement of the rails. These engaging ends of the side rails, 45 B B, are inclosed beneath a saddle, D, upon each side, and to which they are pivotally secured, as at *c*, Figs. 3 and 4. In order that the

pivot-bolt used at this point shall not appear upon the outer face of the saddle and make a disfigurement in the appearance of the device, 50 I recess the inner face of the outer wing of the saddle to receive the head of the pivot-bolt *c*, which is retained in its position by a plate, E, secured within the recess.

F is a central cross-bar, the ends of which are 55 pivotally secured to the side rails by the links or arms G, and upon this central cross-bar I secure a series of coil-springs, H, which, when the bed is open, form a support to the central portion of the mattress. The outer ends of 60 the side rails are pivotally secured in the head and foot sections of the frame A in any convenient and substantial manner. By this construction I produce a bed that, when in its closed position, will serve as an ornamental 65 piece of furniture in the room without disclosing what it really is, as all the parts are hidden within the case, while when the bed is open a sagging of the side rails is prevented by the peculiar construction of the double 70 knuckle-joint, two of the knuckles or cogs of which form, together with their pivots, a lock, which prevents a sagging of the rails at that point, the springs and the cross-rail F preventing a sagging of the mattress in the center. 75 It will be observed that in the closing of the device this bar F, by means of its peculiar connection with the side rails, drops away from the mattress, allowing it to have a free movement in the folding of the bed.

80

What I claim as my invention is—

1. The combination, in a folding bed, of the two-part case A, having the side rails, B B, pivotally secured thereto, with the saddles D, substantially as set forth.

85

2. The combination, in a folding bed, of the two-part case A, saddles D, and side rails B, provided with intermeshing cogs, and having their ends inclosed beneath and pivoted to said saddles, as and for the purposes specified.

FREDERICK SCHRAY.
